Patented Aug. 11, 1959

185,888

STABILIZER FIN FOR BOATS

Julien G. Bamberger, Milwaukee, Wis., assignor to B-T
Company, Inc., Milwaukee, Wis., a corporation of Wis-
consin

Application May 12, 1958, Serial No. 50,836

Term of patent 14 years

(Cl. D71—1)

Fig. 1.

Fig. 2.

Fig. 1 is a perspective view of a stabilizer fin for boats, showing my new design, and looking principally at the top; and

Fig. 2 is a perspective view thereof looking principally at the bottom.

I claim:

The ornamental design for a stabilizer fin for boats, substantially as shown.
